(57) **CLAIM**

The ornamental design for a mirror, as shown and described.

DESCRIPTION

FIG. 1 is a front perspective view of a mirror, showing my new design;

FIG. 2 is rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view of FIG. 2;

FIG. 10 is a partial enlarged view of FIG. 2;

FIG. 11 is a partial enlarged view of FIG. 5;

FIG. 12 is a partial enlarged view of FIG. 6;

FIG. 13 is a partial enlarged view of FIG. 8; and,

The broken lines in the figures are demarcating enlarged areas and form no part of the claimed design.

1 Claim, 14 Drawing Sheets
